UNITED STATES PATENT OFFICE.

CHARLES F. MERRILL, OF NORTH ADAMS, MASSACHUSETTS, ASSIGNOR TO DRAPER CORPORATION, OF HOPEDALE, MASSACHUSETTS, A CORPORATION OF MAINE.

TERRY-LOOM.

1,322,715.

Specification of Letters Patent. Patented Nov. 25, 1919.

Application filed August 15, 1918. Serial No. 250,043.

To all whom it may concern:

Be it known that I, CHARLES F. MERRILL, of North Adams, in the county of Berkshire, in the State of Massachusetts, have 5 invented certain new and useful Improvements in Terry-Looms, of which the following is a specification.

The present improvements relate to the pattern mechanism employed in terry looms 10 for determining the weaving of the terry and plain portions of a fabric to the desired extent and sequence; to the letting back of the fabric under the control of the pattern mechanism in changing between 15 plain and terry weaving so as to avoid slackness in the fabric at these places, and also during the plain weave to secure closeness and compactness; and to the connections between the pattern mechanism and 20 the beat-up motion.

The improvements are illustrated in the accompanying drawings in which—

Figure 1, is a side view of the pattern mechanism. Fig. 2 is a vertical section in 25 the plane indicated by the line 2—2 in Fig. 1. Fig. 3, is a vertical section in the plane indicated by the line 3—3 in Fig. 1. Fig. 4, is a vertical section in the plane indicated by the line 4—4 in Fig. 1. Fig. 5, is a vertical section in the plane indicated by the line 5—5 in Fig. 1. Fig. 6, is a vertical section in the plane indicated by the line 6—6 in Fig. 1. Figs. 7 to 14, are views of the beat-up motion and 35 the take-up and the connections between the transmitting levers of the pattern mechanism and the beat-up motion and the take-up. Fig. 7, is a plan view of the pattern mechanism. Fig. 8, is a vertical section of the beat-up motion shaft with its 40 actuating mechanism in elevation. Fig. 9, is a vertical section in the plane indicated by the line 9—9 in Fig. 10. Fig. 10, is a plan view of the pattern mechanism, beat-up motion, and let-back motion. Fig. 11, 45 is a vertical section of the loom, illustrating the beat-up and let-back motions. Fig. 12, is a detail section of a part of the transmitting devices between the pattern mechanism and the let-back. Fig. 13, is a vertical section in the plane indicated by the

line 13—13 in Fig. 10. Fig. 14, is a detail view of the pattern lever stop.

In terry looms for weaving double pile fabrics such as Turkish towels it is important that sections of plain fabric should be woven as well as sections of the pile fabric since it is customary to make the ends of each towel with alternating stripes of plain and terry fabric. In accordance with 55 the present invention pattern mechanism is employed which automatically governs the change between plain and terry weaving and the extent and distribution of each variety.

As has long been customary, the terry weaving for toweling has been effected through varying the forward extent of the beat-up movement of the reed. For several picks of the shuttle the reed moves forward 60 toward the fell of the cloth partially only so that a gap is left between the picks of weft and the fell of the cloth. Then, the reed is given its full forward movement thus beating up the several picks at once. 65 The terry warp at the full beat-up of the reed is under slight tension whereas the ground warp remains under its full tension. Hence the portions of the terry warp threads which are between the group of 70 picks and the fell of the cloth are looped on both sides of the fabric as the full beat-up of the reed takes place. This has long been customary in forming the terry loops. When plain weaving is done the reed has its 75 full beat-up movement following each pick and, hence, no loops are formed in the terry warp. Therefore, to change between terry and plain weaving simply requires that the beat-up motion should be regulated so that 80 during plain weaving the reed has full forward beats following every pick whereas during terry weaving there is a sequence of 85 partial forward beats of the reed followed by a full forward beat. In accordance with 90 the present invention there are connections between the pattern mechanism and the beat-up motion thereby producing plain and terry sections of fabric under the control of 95 the pattern mechanism.

In changing from the terry weave to the plain weave and back again a slackness in

65

the fabric occurs at the junction between the two varieties of weave. In accordance with the present invention the take-up is coordinated with the pattern mechanism so that the fabric is automatically let back in changing between the two varieties of weave. Also, during the plain weave the fabric is woven loosely as compared with the terry weave and, accordingly, to render the plain weave compact the pattern mechanism is so organized as to let back the fabric at recurring intervals during the plain weave.

In describing the improved mechanism in detail, the pattern mechanism, the beat-up motion, and the let-back motion, will be set forth in the order named.

Pattern mechanism.—Referring to Fig. 1, the crank-shaft 20, of the loom has a bevel gear 21, engaging a bevel gear 22, at the lower end of a vertical shaft 23. At its upper end this vertical shaft has a bevel pinion 24, meshing with a bevel gear wheel loose on a horizontal shaft 26, but normally clutched thereto. Fast on the shaft 26, is a cylindrical hub 27, (Figs. 1, and 6) having a crank stud 28. This hub and crank stud coöperate with a star wheel 29, so as to rotate the star wheel step by step and to lock it against rotation except when engaged by the crank stud.

The star wheel 29, is loose on a shaft 30. Fast with the star wheel is a sprocket wheel 31, carrying a multiplying pattern chain 32, with projections 33, which in this instance are shown equally spaced. When through the rotation of the sprocket wheel 31, a pattern cam 33, reaches its uppermost position, it encounters a shoe 34, of a centrally pivoted lever 35, thereby elevating the shoe and 40 tilting the lever. This lever at its end opposite the shoe has a fork 36, engaging the peripheral groove of a sleeve 37, which is splined to the shaft 30. Normally, the sleeve 37, is maintained in the idle position shown in Fig. 1, by a spring 38, interposed between a collar 39, fixed to the shaft 30, and a star wheel 40, carried by the sleeve 37. When, however, the lever 35, is tilted by a cam 33, on the multiplying chain the star wheel 40, is moved to the right (Fig. 1) compressing the spring 38. This brings the star wheel 40, into coöperation with a cylindrical hub 41, fast on the shaft 26, and a crank stud 42, carried by said cylindrical hub. Accordingly, the shaft 26, (which during the normal running of the loom is continuously rotated) imparts a step by step rotation to the shaft 30, such a step being given each time a cam on the multiplying chain tilts the lever 35.

The shaft 30, has fast on it a sprocket wheel 43, which carries the main pattern chain 44. Accordingly, the main pattern chain is fed step by step at intervals depend-

ing upon the number of the cams 33, on the multiplying pattern chain, and the relation between the gearing which actuates the multiplying chain. In the particular loom illustrated in the drawings the shaft 26 rotates once for each three rotations of the crank 70 shaft (and hence for three picks of the weft); and a cam 33, on the multiplying chain tilt the lever 35, at every eight steps of the star wheel 29, and hence at every twenty-four picks. Therefore, the main pattern chain is fed one step for a large number of picks, in the specified instance illustrated, one step for every twenty-four picks.

The main pattern chain has two sets of cams 45, and 46. These cams are in the form of rollers each loosely turning on a round of the pattern chain. The forward set of cams 45, coöperate with a transmitting "let-back" lever 47. As shown in Fig. 2, the lever 47, has a depending foot 48, which is adapted to be encountered by the cams 45, so that the lever is lifted in turn by each cam 45. This front lever 47, controls the let-back motion. When the let-back lever 47, is lifted by one of the cams 45, the cloth 90 is let back.

The rear set of cams 46, on the main pattern chain coöperates with a second lever 49, also pivoted at its outer end and having a depending foot 50, in the path of the cams. This rear transmitting lever 49, is operatively connected with the beat-up motion. Whenever this lever is lifted by one of the cams 46, the reed is given full forward beats, and plain weaving is done.

The cams 45, and 46, are so distributed on the pattern chain as to produce the lengths and sequence of the terry and plain weaves and to let back the cloth at the desired places.

Before explaining the beat-up and let-back motions and the connections between the same and the transmitting levers, certain special features of the pattern mechanism will be mentioned.

Although the main pattern chain is fed one step in the direction indicated by the arrows in Fig. 2, for a number of picks, nevertheless the chain is long especially for large towels. Accordingly looping means 115 are provided for holding up the bottom of the chain in loops. The descending run of the chain passes down upon an outwardly inclined fixed support 51. Certain of the chain rounds have outwardly projecting pins 52, at both ends as shown in Fig. 1. These pins 52, coöperate with two fixed loopers 53. Each looper is a guide and support for one set of the pins 52, and it inclines downwardly from its outer end inwardly. The links of the pattern chain are directed by the guide plate 51, to the outer ends of the supporting loopers 53, as

shown in Fig. 2. The chain links which are not provided with the pins 52, pass down between the loopers 53, until a round having pins arrives which are caught and held by the loopers; then another sequence of pinless links passes downwardly between the loopers, till another round having pins 52, is stopped by the loopers. Hence, the action of the loopers in connection with the traveling pattern chain with occasional outwardly projecting pins is to gather the bottom of the chain into a series of loops as shown in Fig. 2. The upward run of the pattern chain lifts step by step away from the inner ends of the loopers 53, and as this upward run is completely withdrawn from the loopers the weight of the loops of the chain supported by the loopers suffices to cause the chain loops to ride inwardly down the inclined loopers. The result is that the chain loops itself on the loopers in the manner indicated in Fig. 2.

It is desirable that the pattern chains should be susceptible of hand control particularly in starting up the loom with pattern chains for different sizes and patterns of towels and also to bring them into time when needful. For this purpose a forked hand lever 54, (Fig. 1) is employed. The lower forked end of this hand lever engages a circumferential grooved clutch collar 55, splined to the shaft 26. Normally this clutch collar is maintained in clutching engagement with gear 25, by a spring 56. When it is desired to adjust the pattern mechanism the hand lever 54, is rocked so as to move the clutch collar 55, away from the gear 25, which as heretofore stated, is loose on the shaft 26. A hand wheel 57, is fast on the outer end of the shaft 26. Accordingly, when the clutch 55, is removed from the gear 25, by the hand lever 54, the shaft 26, can be turned by hand with the same effect upon the pattern chains as when the shaft 26, is turned by power.

Also, in order that the main pattern chain may be adjusted with respect to the multiplying chain, the lever 35, (Fig. 1) is provided with an upward extending handle 58, by means of which the sprocket wheel 40, may be brought into coöperative engagement with the crank stud 42, when there is no cam 33, of the multiplying chain in position to tilt the lever 35. When the sprocket wheel 40, is thus brought into co-operation with the crank stud 42, by the handle 58, the turning of the shaft 26, by the handle 57, feeds the main pattern chain.

10 A movable gear cover 59, (Fig. 3) is provided for covering the gears 24, and 25, and the two star wheels and the actuating devices therefor intermediate between them and the gear 25. The cover 59, has hinges 60, (Figs.

1, and 5) connecting it with the fixed inclosing casing 61, so that it may be turned up out of the way when access to the covered parts is desired.

15 A fixed shouldered stop 62, (Fig. 2) limits the downward swing of the levers 47, and 49.

20 At its bottom the multiplying chain passes around an idle sprocket wheel 63, turning on a stud 64, carried by a bracket 65.

25 *Beat-up motion.*—There are several known ways in the art of giving the partial and full forward strokes to the reed. This may be done by moving the crank shaft forward and back; by varying the effective length of the connection between the crank shaft and the lay; or by a movement of the reed itself on the lay. Whatever arrangement is adopted in this respect the effect is to vary the beat-up movement of the reed. In the particular loom illustrated in the drawings, the variation of the beat-up movement is accomplished by moving the reed on the lay through the rocking of a beat-up motion shaft A. The connections between this beat-up motion shaft A, and the reed are substantially as shown in United States Letters Patent of Bardsley No. 937,139, October 19, 1909, in which the beat-up motion shaft corresponding to shaft A, of the present case is designated by the numeral 11.

30 During the terry weave the shaft A, is rocked by a cam B, on the back shaft C. This shaft, as common in terry looms, is geared to the cam shaft of the loom so as to run continuously and so that the speed ratio corresponds with the number of picks for each full forward beat of the reed. This ratio may be any desired. A common ratio is such that the reed is held from full forward movement for two picks and then beats up to its full extent following the third pick.

35 A cam lever D, at its front end is loosely hung on the rock shaft and at its rear end has a roll a, traveling in the groove of cam C. The lever D, is adapted to be coupled and uncoupled from the shaft A. During the terry weave it remains coupled to the shaft A, and hence the shaft is rocked back and forth at every revolution of the cam C. The cam is so shaped that the shaft A, is rocked for every full beat-up stroke of the reed, in the illustrated instance, at every third forward beat of the lay.

40 In order to do plain weaving the cam lever D, is uncoupled from the shaft A. When thus uncoupled the cam lever at its forward end simply turns idly on the shaft A; and the shaft is maintained in such position that the reed at every forward beat makes its full stroke. The coupling and uncoupling of the cam lever to the beat-up motion shaft A, are automatically effected by the rise and fall of the transmitting lever

49, as controlled by the set of cams 46, on the main pattern chain 44.

Fast on the beat-up motion shaft A, is a crank arm E, having a slot b. A latch F, is pivoted to the cam lever D. Its latching tooth c, always occupies a slot d, in the cam lever D. The latch is swung in one direction by a spring G. When this spring is free to act it projects the latch tooth into the slot b, in the arm E, thereby locking the cam lever to the shaft A, so that said shaft is then under the control of cam C. In order to stop the cam actuation of the shaft A, it is simply necessary to withdraw the latch tooth from the slot in the arm E, by moving the latch against the stress of the spring G.

For this purpose there are connections between the latch and the transmitting lever 49, of the pattern mechanism. A link 66, connects the rear end of the latch with a lever I, pivoted at its middle upon the shaft A. The other end of the lever 67, is connected by a wire 68, with the inner free end of the lever 49. This wire between the levers 49, and I, extends through a fixed coiled wire sheath 69, and fixed guides 70. When the transmitting lever 49, is lifted by one of the cams 46, on the main pattern chain the latch is withdrawn from the arm E, the reed always has its full forward beat, and plain weaving is done. When, however, the lever 49, is no longer supported by a cam 46, of the main pattern chain it drops and the spring G, causes the latch to reengage the arm E, and the terry weave is resumed. Each cam 46, dwells at its highest point and holds the lever uplifted until the next feed step of the main chain 44.

40 By having a succession of cams 46, on the pattern chain so that the transmitting lever 49, is maintained uplifted at successive steps of the main pattern chain, the plain weave action continues uninterruptedly. When 45 the rounds of the pattern chain have no cams 46, the transmitting lever 49, is down and terry weaving is done.

The connections between the beat-up motion shaft A, and the reed J, are shown in Fig. 11. In principle they are similar to those of the Bardsley patent mentioned above. At each side of the loom, the shaft A, has a crank arm f, connected by a sledged link g, to a toggle link h, pivoted at its middle to a bracket i, carried by the lay L. The toggle link h, is also pivoted to a second toggle link j, pivotally connected to a swinging arm k, to which is fastened the bottom rail l, of the swinging reed. These parts 60 f, g, h, i, j, and k, are at each side of the loom. A spring m, connected to the rear end of each toggle link n, acts to straighten the toggle, as shown in Fig. 11, so that the reed is then locked and is prevented from

swinging. When the high part of cam B, 65 acts on lever D, the shaft A, is rocked in the direction of the neighboring arrow (Fig. 11), when latched to said lever, as shown in Fig. 11, thereby breaking the toggle h, j, and swinging the reed rearwardly. 70

When the tooth c, of the latch F, is removed from the slot b, in arm E, as shown in Figs. 8, and 9, thereby unlatching the shaft B, from lever D, the spring H (Figs. 8, 9, and 11), holds the shaft A, in the position shown in Fig. 8, with an adjustable stop n, carried by the shaft resting on a fixed girt o, and the toggle h, j, is straightened by the spring m.

The spring H, is connected at one end to 80 the cam lever D, and at the other end to a depending foot e of the arm E, which is fast on the shaft A.

The arm E, likewise has a headed stud p, fast on its inner end which extends through a slot q, in the cam lever D, and prevents any lateral displacement of said lever. The slot q, is long enough to permit the play of the cam lever without affecting the beat-up motion shaft during the plain weaving. 90

Let-back motion.—The take-up mechanism illustrated is similar to that shown in reissued United States Letters Patent to Nevin Reissue No. 12,944, April 20, 1909. Only enough of this mechanism is shown to 95 enable the connections between the same and the pattern mechanism to be understood.

As in said Nevin patent the prime gear N, of the take-up gear train for rotating the take-up roll O, meshes with a pinion P, 100 which is loose on a drive shaft Q. This drive shaft has a worm wheel R, fast thereon which is driven from a worm shaft S, constantly rotated from the cam shaft. A clutch sleeve T, splined to the shaft is normally kept in clutching engagement with the pinion by means of a spring U, so that during the normal operation of the loom the take-up roll is continuously rotated. The gearing between gear N, and the take-up roll O, is not shown, being identical with that of said Nevin patent. In order to let back the cloth and warps, the clutch sleeve T, is removed from engagement with the pinion P, and, accordingly, the stretch on the cloth and warps rotates the gear N, and pinion P, backwardly to the desired extent. In all of these respects the mechanism is like that of the aforesaid Nevin patent. 110

In accordance with the present invention 120 the unclutching movement of the clutch T, is effected by the cam rolls 45, on the main pattern chain lifting the transmitting let-back lever 47. A wire 71, connected with the free end of the lever 47, extending 125 through a coiled wire sheath 72, and guides 70, and 73, connects with a bell crank lever 74, which in turn is connected by wire 75,

to a forked clutch lever 76, which co-operates with the clutch T. When the transmitting let-back lever 47, is lifted by one of the cams 45, of the main pattern chain the said forked clutch lever 76, is moved in the proper direction to unclutch the take-up thereby permitting the cloth and warps to let back. When a lifting cam 45, passes from beneath the lever 47, it drops and the spring 10 stores the clutching engagement with the take-up train of gears and the take-up action upon the cloth and warps continues.

The cams 45, on the main pattern chain are so located that the take-up train of gears is released to let back the cloth and warp on changing from the terry weave to the plain weave, and again on changing from the plain weave to the terry weave.

Also, the clutch T, is shifted to let back the cloth and warp from time to time during the plain weaving. In the particular embodiment illustrated the cams 45, are arranged on the main pattern chain during the plain weaving one after the other on the 25 succeeding rounds of the pattern chain so that the let-back action occurs during plain weaving at each step given to the main pattern chain, that is to say whenever a cam on the multiplying chain swings the lever 35. 30 In the illustrated construction this occurs at every twenty-fourth pick.

The main pattern chain dwells in the position shown in Fig. 2; and if then a cam 45, is presented it is at the uppermost part 35 of the sprocket wheel 43. The foot 48, of the lever 47, is just at the right of this uppermost cam as indicated in Fig. 2. Consequently, the lever 47, is down and the take-up is in action. At the next step of the 40 main pattern chain the cam 45, (as shown in Fig. 2) rises, encounters the foot 48, thereby raising the lever 47, and permitting the cloth and warps to let back, but immediately thereafter moves to its highest position passing completely from under the foot 48, and therefore, permitting the lever 47, to immediately drop. Accordingly, the let-back action occurs once only for each cam 45, of the main pattern chain.

50 *Mode of operation.*—Assuming that terry weaving is being done, the beat-up motion shaft A, is rocked by the cam B, after a pre-determined number of picks so that the reed is given its full forward stroke beating up several picks of weft at once and hence forming the terry loops. Also, during the terry weave the take-up acts uninterrupted. Also during the terry weave, the pattern mechanism driven from the 55 crank shaft of the loom continues in action giving step by step motions to the multiplying chain and hence less frequent step by step motions to the main pattern chain.

The change from the terry weave to the

plain weave is determined by the cams 46, 65 on the main pattern chain. When one of these cams 46, lifts the lever 49, the cam lever, D, is unlatched from the beat-up motion shaft A. As a consequence, the cam actuation of said shaft ceases and it stands in 70 a position to cause the reed to beat fully forward after each pick. The cam 46, holds the lever 49, up until the next forward movement of the pattern chain and, if a longer portion of plain weave is required, 75 cams 46, are successively brought into action to maintain the lever 49, uplifted until the desired length of plain cloth has been woven. When the last cam 46, passes from beneath the lever 49, the cam lever D, is again coupled to the beat-up motion shaft A, and the terry weave is resumed.

It is important that the cloth and warps should be let back in changing from terry to plain weaving and during the plain weaving 85 in order that the plain weaving may be compact and closely joined to the terry weave. The letting back is effected by the second set of cams 45, on the main pattern chain in co-operation with the let-back lever 90 47. When one of the cams 45, approaches its highest point it raises the lever 47, and then permits it to drop. This lifting of the let-back lever results in unclutching the take-up mechanism from its drive shaft so 95 that the strain of the cloth and warps causes the take-up to let back sufficiently to render the cloth compact. The let-back having occurred the take-up is immediately re-clutched to its driving mechanism. The 100 cams 46, are so arranged on the pattern chain that the let-back occurs at intervals throughout plain weaving. Also the cams 46, can be so arranged that the cloth and warps are let back in changing from plain 105 weaving to terry weaving.

The pattern chains can be adjusted and timed by hand by means of the hand levers 54, and 58, and the hand wheel 57.

I claim—

1. A terry loom having a beat-up motion shaft, a continuously running cam, a cam lever loosely hung on said shaft and acted upon by said cam, a crank arm fast on said shaft, a coupling latch carried by said cam lever, a spring acting to move said latch to couple the cam lever and crank arm together; a limiting slot in the cam lever, a stud on the crank arm extending into said slot and a spring connecting the lever and arm, in combination with pattern controlled means for moving said latch to uncouple the cam lever from the crank arm when plain weaving is to be done.

2. A terry loom having a beat-up motion 125 shaft, a continuously running cam, a cam lever loosely hung on said shaft and acted upon by said cam, a crank arm fast on said

6
shaft, a coupling latch carried by said cam lever, and a spring acting to move said latch to couple the cam lever and crank arm together, in combination with pattern controlled means for moving said latch to uncouple the cam lever from the crank arm when plain weaving is to be done.

3. A terry loom having a beat-up motion shaft, a continuously running cam, a cam lever acted upon by said cam, a coupling latch carried by said cam lever, and a spring acting to move said latch to couple the cam lever and shaft together, in combination with pattern controlled means for moving 10 said latch to uncouple the cam lever from the shaft when plain weaving is to be done.

4. A terry loom having a beat-up motion shaft, a continuously running cam, a cam lever acted upon by said cam, and a coupling 20 latch carried by said cam lever normally coupling the cam lever and shaft together, in combination with pattern controlled means for moving said latch to uncouple the cam lever from the shaft when plain weaving 25 is to be done.

5. A terry loom having a take-up mechanism including a pinion, a clutch splined to said shaft, and a spring acting to move the clutch to engage the pinion, in combination 30 with a clutch actuating lever movable to disengage said clutch from said pinion, and pattern mechanism controlling the action of said lever.

6. A terry loom having a take-up mechanism including a pinion, a drive shaft and a clutch splined to said shaft and normally engaging the pinion, in combination with a clutch actuating lever movable to disengage 35 said clutch from said pinion, and pattern mechanism controlling the action of said lever.

7. A terry loom pattern mechanism having a multiplying chain with cams, a sprocket wheel for said chain, driving mechanism imparting a step by step movement 40 to said sprocket wheel and chain, a main pattern chain having two sets of cams, a sprocket wheel for said main chain, intermittently acting driving mechanism controlled by the cams on the multiplying chain and acting to move said main chain step by step, and two transmitting levers actuated by 45 said two sets of main chain cams respectively, in combination with mechanism controlled by one of said levers to change between plain and terry weaving, and mechanism controlled by the other lever to disconnect the take-up from its drive to let back the cloth and warps.

60 8. A terry loom pattern mechanism having a main pattern chain having two sets of cams, a sprocket wheel for said main chain, intermittently acting driving mechanism to move said main chain step by step,

and two transmitting levers actuated by 65 said two sets of main chain cams respectively, in combination with mechanism controlled by one of said levers to change between plain and terry weaving, and mechanism controlled by the other lever to let 70 back the cloth and warps.

9. A terry loom pattern mechanism having intermittently acting driving mechanism to move said main chain step by step, and two transmitting levers actuated by 75 said two sets of main chain cams respectively, one of said levers being maintained in active position by a cam during the dwell of the pattern chain, and the other lever moving back and forth as one of its controlling cams 80 passes it, in combination with mechanism controlled by the first of said levers to change between plain and terry weaving, and mechanism controlled by the other lever to disconnect the take-up from its drive to 85 let back the cloth and warps.

10. A terry loom pattern mechanism having, in combination, a multiplying chain with cams, a sprocket wheel for said chain, driving mechanism imparting a step by step 90 movement to said sprocket wheel and chain, a main pattern chain, a sprocket wheel for said main chain, intermittently acting driving mechanism controlled by the cams on the multiplying chain and acting to move said 95 main chain step by step, and a transmitting lever actuated by said chain cams.

11. A loom pattern mechanism having a multiplying chain with cams, a drive shaft therefor, a gear loose on said shaft for driving it, a clutch normally connecting said gear and shaft, a hand moved clutch lever for disconnecting said clutch and gear, and a handle on said shaft for turning it when so disconnected, in combination with a main 105 pattern chain, a movable wheel connected with said main pattern chain and adapted when moved to be driven by said shaft, and a lever controlled by the cam on the multiplying chain to move said wheel into engagement with said shaft, said lever also having a handle to enable said engagement to be hand effected.

12. A loom pattern mechanism having a multiplying chain with cams, a drive shaft 115 therefor, a gear loose on said shaft for driving it, a clutch normally connecting said gear and shaft, a hand moved clutch lever for disconnecting said clutch and gear, and a handle on said shaft for turning it when 120 so disconnected, in combination with a main pattern chain, a movable wheel connected with said main pattern chain and adapted when moved to be driven by said shaft, and a lever controlled by the cam on the multiplying chain to move said wheel into engagement with said shaft.

13. A loom pattern mechanism having a

main chain, a multiplying chain with cams, and a lever controlled by the cams on the multiplying lever to bring said main chain into action, said lever also having a handle to enable the action of the main chain to be hand effected.

14. A loom pattern mechanism having a multiplying chain with cams, a main pattern chain controlled by the cams on the multiply-

ing chain, and an automatic drive for said 15 chains, in combination with hand controlled means for disconnecting the automatic drive and for adjusting the time of both chains, and the time relation between the two chains.

In witness whereof, I have hereunto 20 signed my name.

CHARLES F. MERRILL.
